In Great Britain July 15, 1943

3 Claims. (Cl. 189—34)

1

This invention relates to the construction of floors of buildings (including roofs) and is directed towards the production of an improved floor construction employing sheet material pressed into appropriate shape.

The invention is particularly suitable for use with pressed steel members, but may also be applied to other sheet materials such as plastics.

Advantages of the invention include lightness of construction providing economy in the actual unit and still further economy in the supporting structure, due to the decrease in dead weight of the floor or roof. Further advantages are that all the units can be erected and attached to the supporting structure from the top, therefore no staging is required to put the units into place, or to secure the units, one to the other, to complete the floor or roof. Another advantage relates to the attachment of the floor boards or other surface material direct to the top of the steel unit, without the need for any form of nailing strips or other attaching media.

The primary object of the invention is to provide a floor beam formed of sheet material and having a primary web member at one side of the top flange and a secondary web member at the other side thereof.

Another object is to provide a floor beam of sheet material and having a primary web member at one side of the top flange and a secondary web member at the other side thereof, said primary and secondary web members being so joggled that the joggle of the primary web of one beam fits into the joggle of the secondary web of the adjoining beam.

Several beam units of the present invention may be connected together in the fabricating shops in such a manner to provide air-conditioning ducts as part of the floor construction.

With these and other objects in view the invention consists in the improved constructions now to be described in relation to the accompanying drawings, the novel combinations being set out in the claims which follow.

In these drawings:

Fig. 1 shows in elevation one form of floor unit according to the invention, with a portion of the adjacent unit on the left thereof.

Fig. 2 shows an end elevation of part of the unit shown in Fig. 1.

2

Fig. 3 shows a section through a floor according to the invention with the units resting on the top flange of a main girder.

Fig. 4 is a similar view for the case in which the bottom of the units come below the top flange of a main girder.

Fig. 5 illustrates the suspension of ceiling sheet bearers from the lower flanges;

Fig. 6 illustrates a modification for large spans in which the webs of the units are of openwork construction.

Referring first to Figs. 1 and 2, the floor unit has a top flange 1, a primary web 2, a bottom flange 3 and a secondary web 4 for engagement with the web 2 of the adjacent unit. The bottom flange 3 may be on the opposite side of the primary web 2 to that illustrated. Interengaging joggles 9, 10 are formed in the webs 2, 4.

The web 2 has at appropriate intervals stiffening depressions 5 formed therein and the webs have interengaging loops 6, 60 formed therein. Cotters 7 engage in these loops and clamp the secondary webs 4 to the primary webs 2 of adjacent units, holes 8 being provided in the flanges 1 for insertion of the cotters 7.

Alternative fixing to the cotter and loop is a hollow eyelet on the web 2 engaging a hole in the web 4 and being bent over by an expanding tool or spot welds between buttons formed on the webs 4 at intervals.

The engaging tops of the web leave a slightly tapering space 11 into which may enter nails for fixing boarding.

The bottom flange 3 has an upturned end 12 and has a strengthening flat 13 welded thereto to increase the section modulus when required.

Referring next to Fig. 3, adjacent units rest with their bottom flanges 3 upon a main girder 15 with a space 14 between them, a jointing member 16 holds the adjacent units together.

In the example shown in Fig. 4 the bottom flanges 3 are cut away and the webs 2 rest on the beam.

Hook bolts may be used to secure the bottom flanges of the floor beams to the main girders 15.

Asbestos cement or similar corner pieces 17, 18 with bearing portions 19 and stiffening membrane 20 at intervals bear against the upper surfaces of the lower girder flanges to mask the girder and give fire protection.

Ceiling corners 21 rest against these corner pieces and are supported at the tops by ceiling bearers 22, also of asbestos cement or similar material.

These bearers 22 have hooked ends 23, Fig. 5, which hang over the upstanding portions 12 of the bottom flanges of the units.

Fig. 3 shows a floor having tongue-and-groove boards 24 secured by nails 25 which enter the space 11, Fig. 1.

In Fig. 4 a "composition" floor 26 is shown as laid over the floor members.

Referring now to Fig. 6, which is suitable for floors having large spans between main supports, the primary web members 2 of the previous figures are not continuous sheets as in the previous examples but have portions 27, 28 connected by diagonal members 29, welded thereto, forming an open framework construction.

At the supports connecting to the girder 15 are welded plates 30 and shelf angles 31 support the lower flanges 3 of the floor beams.

In the drawings the tension flange members 3 are shown as on the opposite side to the upper flange members 1, but they may if desired, be placed on the same side.

The invention is not restricted to the details above described but includes all constructions and modifications coming within the ambit of the claims which follow.

We claim:

1. A floor beam formed of unitary sheet material having a top flange, a bottom flange, a primary web connecting the top flange at one end to the bottom flange, a secondary web at the other end of said top flange, said primary web and said secondary web being joggled with a lower portion offset in relation to the upper portion, the joggle of said primary web adapted to interfit with the joggle of the secondary web of an adjoining beam of the same shape, loops provided in the primary and secondary webs below the joggles with their axes vertical, the loop on the primary web adapted to interfit the loop on the secondary web of an adjoining beam of the same shape, and the top flange having an opening above one of the loops whereby a cotter can be inserted vertically from above to engage a loop to secure adjoining webs together.

2. A floor beam formed of unitary sheet material having a top flange, a bottom flange, a primary web connecting the top flange at one end to the bottom flange, a secondary web at the other end of said top flange, said primary web and said

secondary web being joggled with a lower portion offset in relation to the upper portion, the joggle of said primary web adapted to interfit with the joggle of the secondary web of an adjoining beam of the same shape, with the lower portions of said adjoining secondary web in contact with said primary web, and the upper portion of said secondary web spaced from said primary web to permit the application of nails for securing the floor boards to the floor beams, loops provided in the primary and secondary webs below the joggles with their axes vertical, the loop on the primary web adapted to interfit the loop on the secondary web of an adjoining beam of the same shape, and a top flange having an opening above one of the loops whereby a cotter can be inserted vertically from above to engage the loop to maintain the webs in nail receiving cooperation.

3. A floor beam formed of unitary sheet material having a top flange, a bottom flange, a primary web connecting the top flange at one end to the bottom flange, a secondary web at the other end of said top flange, said primary web and said secondary web being joggled with a lower portion offset in relation to the upper portion, the joggle of said primary web adapted to interfit with the joggle of the secondary web of an adjoining beam of the same shape, loops provided in the primary and secondary webs below the joggles with their axes vertical, the loop on the primary web adapted to interfit the loop on the secondary web of an adjoining beam of the same shape, and the top flange having an opening above one of the loops whereby a cotter can be inserted vertically from above to engage a loop to secure adjoining webs together, said primary web having a stiffening depression below said loops.
